ABSTRACT OF THE DISCLOSURE

An accumulator provided with a plurality of movable carriages between sheaves for supporting a loop of material. Means is provided for sequentially widely spacing the carriages longitudinally as the sheaves move apart, and for returning the carriages to at least substantially abutting positions when the sheaves are moved relatively toward each other into their retracted terminal position. Such means takes the form of magnetic coupling means between successive pairs of carriages and the rearmost carriage and the movable sheave, the coupling means progressively increasing in coupling strength toward the movable sheave, and cooperating stop means on the frame and dogs on the carriages for sequentially disengaging the couplings and for holding the respective carriages at predetermined longitudinal positions as the sheaves move apart.

BACKGROUND OF THE INVENTION

Field of the invention

The invention relates to a horizontal accumulator for elongated flexible material. The accumulator is adapted to be introduced into a system for fabricating and/or treating such material; it permits the material to be slowed or held from travel at one end of the accumulator while the material continues to travel at the other end of the accumulator.

Description of the prior art

Horizontal accumulators have been used heretofore, but such prior accumulators have not been altogether satisfactory when employed with heavy elongated flexible material such as cables of large diameter. Although such accumulators have provided for the guiding support of the one or more lower runs of heavy material such as cable between the relatively movable sheaves thereof, they have made little or no provision for the guiding support of the one or more upper runs of the cable extending between the sheaves. In many instances the cable would at times sag sufficiently to engage and be scuffed by fixed members such as parts of the frame as the cable travelled therewith. This was a serious difficulty, particularly if the cable were sheathed, since the scuffing in some cases proved to be serious enough to cause the rejection of considerable lengths of very expensive cable.

Summary of the invention

In the illustrative embodiment, the accumulator is shown handling a sheathed cable of relatively large diameter, such cable having issued from a continuous vulcanizing chamber and travelling toward a take-up or reeling station. The accumulator permits the cable to continue its travel at constant speed through the vulcanizing chamber while the leading end of the cable beyond the accumulator is held fixed, as by being clamped, while the substitution of an empty take-up reel is being made for a full take-up reel. In such use, the sheaves of the accumulator move relatively away from each other from

2

a starting position (FIG. 1) to a terminal position (FIG. 3). Alternatively, when employed in a manner not illustrated, the accumulator may be used, as at the feeding end of a sheathing extruder continuous vulcanizing chamber system, to provide a supply of unsheathed cable to the extruder. In such use, the sheaves of the accumulator are initially positioned as in FIG. 3. When it is necessary to splice the leading end of a fresh reel to the trailing end of the cable being fed into the extruder, such trailing end is clamped, and the leading end of the new cable is spliced thereto. During this time, cable is continuously supplied to the extruder from the accumulator, the sheaves then travelling toward each other toward the position of FIG. 1.

In accordance with the invention there is provided a plurality of intermediate carriages which are movable on a track disposed longitudinally of the frame, such track also supporting a carriage upon which the second sheave is rotatably mounted. Each of the intermediate carriages has a cable supporting roller on the upper portion thereof, such rollers being adapted to support the upper runs of the cable between the sheaves when the second sheave is moved to extend such runs sufficiently for them to sag appreciably.

The accumulator includes means for causing the intermediate carriages to travel as a coupled train coupled to the carriage supporting the second sheave in the initial portion of the travel of the latter. During such travel of the second sheave, the intermediate carriages are progressively uncoupled from the trailing end of the train and are held at predetermined longitudinally spaced positions so as to furnish proper support for the upper runs of the cable in the accumulator. Upon the return travel of the second sheave toward the first sheave, the intermediate carriages are progressively picked up and coupled to the trailing end of the train of intermediate carriages.

BRIEF DESCRIPTION OF THE DRAWINGS

The above and further objects and novel features of the invention will more fully appear from the following description when the same is read in connection with the accompanying drawings. It is to be expressly understood, however, that the drawings are for the purpose of illustration only, and are not intended as a definition of the limits of the invention.

In the drawings, wherein like reference characters refer to like parts throughout the several views,

FIG. 1 is a schematic simplified view in side elevation of the illustrative accumulator with the movable sheave retracted to a position adjacent the fixed sheave thereof;

FIG. 2 is a view similar to FIG. 1 but with the movable sheave in a position intermediate its permissible range of travel;

FIG. 3 is a view similar to FIGS. 1 and 2 but with the movable sheave in its fully extended position, furthest from the fixed sheave;

FIG. 4 is a somewhat schematic fragmentary view in plan of the accumulator with the movable sheave thereof positioned as in FIG. 1;

FIG. 5 is a fragmentary view in side elevation of the portion of the accumulator illustrated in FIG. 4;

FIG. 6 is a view in side elevation on a larger scale than that employed in FIGS. 4 and 5, the accumulator being broken through in two longitudinally spaced positions, the first, second, and ninth and tenth intermediate carriages, numbered from the left in FIGS. 1-5, inclusive, being shown;

FIG. 7 is a view in horizontal section through the accumulator, the figure showing the second, ninth, and tenth intermediate carriages, the section being taken along the line 7—7 of FIG. 6; and

FIG. 8 is a view in transverse section through the accumulator, the section being taken along the line 8—8 of FIG. 6.

DESCRIPTION OF THE PREFERRED EMBODIMENT

Turning now to the drawings, the illustrative accumulator is shown handling a sheathed vulcanized cable 11 which enters the accumulator along a horizontal path 10. The path 10 lies along the upper side of a first fixed single-grooved sheave 17 which is mounted tipped from the vertical on an axle 18, as shown in FIG. 4. The cable proceeds to a first groove 12 in a movable double-grooved sheave 14, returns in a lower run 15 to pass into the bottom of the groove 16 in the sheave 17. After passing 180° about sheave 17 the cable 10 extends in a third horizontal run 19 thereof to the upper portion of the second groove 20 in the movable sheave 17. From groove 20 the cable passes in a second lower horizontal run 21 to the left to be withdrawn from the accumulator. As above explained, in the described installation of the illustrative embodiment the movable sheave 14 is initially retracted into the position shown in FIG. 1, the sheave 14 travelling toward the terminal position shown in FIG. 3 in storing cable 11 therein. (Alternatively, if the accumulator were employed to supply cable, the movable sheave 14 would be initially positioned as in FIG. 3, and, as the accumulator supplies the cable, the sheave 14 would move toward the terminal position shown in FIG. 1.)

As shown in FIGS. 4-8, inclusive, the accumulator has an elongated horizontal hollow frame which is generally designated 22, such frame being formed of a plurality of pairs of laterally spaced uprights 24 disposed at intervals along the length of the frame. The frame has suitable upper longitudinal members 25 and cross members 26. Extending along the frame intermediate its height and on opposite sides thereof are two parallel horizontal channel members 27 forming tracks. Movable along such tracks is a carriage 29 on which the movable sheave 14 is journaled. Carriage 29 is made up of two similar side members 30 connected by a rear or right-hand cross member 31 and a front or left-hand cross member 32. The movable sheave 14 is disposed between the side frame members 30 and is journaled to rotate in a vertical plane upon an axle secured to members 30, as shown. The carriage 29 is supported on the track members 27 by pairs of oppositely projecting forward and rear upper rollers 34 which overlie the tracks, and is prevented from upward escape from the tracks by two oppositely projecting central lower rollers 35 which underlie the tracks.

The carriage 29 is pulled to the right, whereby to place the runs 10, 19 and 15, 21 of the cable 11 under tension, by means including a cable 40, one end of which is secured to the right-hand end of the carriage 29, such cable extending to a winding drum 37 mounted upon the frame of the accumulator. Drum 37 is driven in the direction to wind up the cable 40 by a torque motor 36 which is connected to the winding drum as by a chain and speed reducing means generally shown at 39. The accumulator is protected against destructive shock, by reason of travel of the carriage 29 at appreciable speed into its right-hand terminal position, by means of a shock absorbing abutment 38 which is interposed between portions of the frame including uprights 24 and the carriage 29. The accumulator is also provided with fixed lower cable guiding rollers 41 which are journaled upon axles extending between opposite uprights 24. When the sheave 14 is moved to the right into either an intermediate or the terminal position thereof, the lower runs 15, 21 of cable 11 ordinarily sag slightly and are then supported by the rollers 41, as shown in FIGS. 2 and 3.

In accordance with the present invention there is provided a plurality (10 shown) of similar intermediate carriages 42 disposed to be supported by and to move along the tracks 27 between the fixed sheave 17 and the movable

sheave 14. Each of carriages 42 has a transversely extending roller 50 on the top thereof, such roller being disposed to support and guide the upper runs 10, 19 of cable 11 when such runs sag appreciably. In the retracted position of carriage 29 (FIG. 1), the carriages 42 are disposed in coupled abutting relationship, the first or left-hand carriage 42 abutting a fixed stop 43 (FIGS. 4 and 5) which is fixedly secured to the frame of the accumulator. Each of the carriages 42 has two laterally spaced similar opposite side members 44, the side members being connected by a forward transverse member 45 and a rear transverse member 46. Each of members 46 is made of magnetic material such as steel. Each of the carriages has pairs of oppositely projecting forward and rear rollers 47 thereon, such rollers overlying and being supported by the tracks 27. The carriages 42 are retained upon the tracks by oppositely extending central lower rollers 49 which engage the bottom surfaces of the tracks 27. Journalled centrally of each carriage 42 transversely thereof is the above-mentioned cable supporting roller 50.

Each of the second to the seventh intermediate carriages 42 (counting from the left) has mounted on the forward cross member 45 thereof a centrally disposed permanent magnet 51. The forward (left) cross member 45 of the first carriage is devoid of such magnet. The eighth, ninth, and tenth intermediate carriages 42 and the forward cross member 32 of the carriage 29 are provided with two permanent magnets 51 which are disposed laterally spaced on opposite sides of the longitudinal center lines of the carriages, as shown in FIG. 7. In the illustrative embodiment all of the magnets 51 are of the same size and shape and have the same field strength. The magnets, which are made of Alnico, are generally circular cylindrical, and are cross slotted at their outer, free ends to form four equally spaced poles. One set of opposing poles are north, and the other set are south poles. It is obvious that different types of magnets may be substituted for magnets 51 if desired.

In accordance with the invention, the magnetic attractions between successive intermediate carriages 42 and that between the right-hand carriage 42 and the carriage 29 increase in the direction from left to right. This result is attained, with identical magnets 51, by the use of shims 52 of non-magnetic material, such as brass, of different thicknesses upon the rear cross members 46 of the carriages 42. As above noted, members 46 are made of magnetic material and thus form armatures for the respective magnets 51. In a typical accumulator in accordance with the invention wherein it is desired that the magnetic attractions between successive carriages shall increase in 10 lb. increments in the direction from left to right, the shim employed between the first and second intermediate carriages 42 is .048" in thickness, the shims decreasing progressively in thickness until no shim is provided on the rear cross member of the sixth intermediate carriage 42, that is, at the sixth magnetic coupling. At such coupling the coupling force is 70 lbs. The seventh, eighth, ninth, and tenth magnetic couplings, each of which employs two magnets 51, have coupling forces, respectively, of 80, 90, 100, and 110 lbs. The non-magnetic shims 52 employed at such seventh to the tenth couplings decrease progressively in thickness from .024" at the seventh coupling to .012" at the tenth. It is thus apparent that as the carriage 29 carrying the movable sheave 14 initially travels to the right from its position in FIG. 1, it carries with it the train of coupled carriages 42. It is also apparent that the carriages 42 may be progressively uncoupled from the left-hand end of the train by a coupling breaking restraining force applied to the carriage which is then at the left end of the train without uncoupling the other carriages from the train.

The accumulator includes means for sequentially uncoupling carriages from the left-hand end of the train of carriages and leaving them at a position longitudinally of the range of travel of the movable sheave of the ac-

cumulator to afford proper support for the upper runs 10, 19 of the cable 11. Such means includes a pair of oppositely extending dogs on each carriage 42, the dogs being generally aligned with the forward cross member 46 of each carriage and being designated 54-63, inclusive, from the first to the tenth carriage. The dogs 54-63, inclusive, are located at progressively decreasing height on the carriages, as is shown somewhat schematically in FIGS. 1-3, inclusive, and structurally in FIGS. 6 and 7. Cooperating with the respective dogs are pairs of oppositely inwardly extending stops affixed to the frame at positions spaced longitudinally thereof, such stops being designated 64-73, inclusive, in the direction from left to right, each pair of such stops being located at the respective position longitudinally of the frame at which a carriage 42 is to be positioned when it has been uncoupled from the train of coupled carriages 42. The stops 64-73, inclusive, are disposed at heights above the tracks 27 which progressively decrease in the direction from left to right, each stop being positioned at a height such that the dogs on carriages 42 to the right of the carriage to be held by such stop pass freely thereunder, whereas the dogs on carriages to the left of such carriage are disposed vertically above the stop in question.

Such action is evident in FIGS. 1-3; in FIG. 2 the first five carriages 42 are shown as being held from further travel to the right by their respective stops, the last five carriages remaining coupled to the carriage 29 so that they travel therewith to the right. Upon further travel of the carriage 29 with the carriages coupled thereto to the right, such carriages 42 are progressively uncoupled and are held against travel to the right by the stops 69-73, inclusive. Since the upper runs 10, 19 of the cable travel to the right, engagement of such runs with the supporting roller guides 50 on the carriages 42 held by their respective fixed stops maintains the dogs on the carriages in contact with such stops, so that the uncoupled carriages 42 are securely retained in the desired longitudinally spaced positions.

Upon travel of the carriage 29 from its extended position of FIG. 3 toward the retracted position of FIG. 1 the intermediate carriages 42 are progressively coupled to carriage 29 and then to each other. The cooperation between the dogs 59-63, inclusive, and stops 64-73, inclusive, is such that the carriages 42 can travel freely to the left as they are progressively picked up by and coupled to the left-hand end of the train of coupled carriages. Accordingly, the accumulator is automatic in its action, requiring no operator attention.

Although only one embodiment of the invention has been illustrated in the accompanying drawings and described in the foregoing specification, it is to be especially understood that various changes, such as in the relative dimensions of the parts, materials used, and the like, as well as the suggested manner of use of the apparatus of the invention, may be made therein without departing from the spirit and scope of the invention, as will now be apparent to those skilled in the art.

I claim:

1. In an accumulator for elongated flexible material, 60 said accumulator having a generally horizontal longitudinally extending frame, a first carriage movable longitudinally along the frame, a sheave journaled on the first carriage and forming at least one storage loop having longitudinally extending runs, and means for constantly urging the first carriage rearwardly along the frame to tension the runs of material, the improvement which comprises a plurality of longitudinally aligned intermediate carriages disposed forwardly of the first carriage, means mounting the intermediate carriage for longitudinal movement along the frame, each carriage having a material guide means thereon lying below a longitudinal run of the material and adapted to be engaged by

such run when the run sags appreciably upon rearward movement of the sheave to extend the runs of material, magnetic means to couple successive intermediate carriages together into a train and to couple one end of the train to the first carriage, the magnetic coupling means between successive pairs of intermediate carriages and between the end of the train and the first carriage progressively decreasing in coupling force in the direction from the first carriage to the free end of the train remote from the first carriage, and means progressively to detach carriages from the free end of the train by breaking the magnetic coupling between them and the next adjacent carriage in the train and to space the thus detached carriages longitudinally of the frame upon rearward movement of the first carriage.

2. Apparatus as claimed in claim 1, wherein the means progressively to detach intermediate carriages from the train of carriages comprises a series of longitudinally spaced stops affixed to the frame, and dogs on each of the intermediate carriages adapted to engage only a respective one of said stops to detach said intermediate carriages successively from the train and to locate the detached carriages at the successive stops.

3. Apparatus as claimed in claim 2, wherein the dogs on the intermediate carriages in the train project successively further in one direction away from such carriages from carriage to carriage in the direction away from the first carriage, and the stops on the frame are located successively further in said one direction but toward the dogs in the direction away from the first carriage.

4. Apparatus as claimed in claim 2, wherein the dogs on the intermediate carriages in the train project successively further in a vertical direction away from such carriages from carriage to carriage in the direction away from the first carriage, and the stops on the frame are located successively further in said vertical direction but toward the dogs in the direction away from the first carriage.

5. Apparatus as claimed in claim 2, wherein there are longitudinally spaced sets of stops on the frame, each set of stops including two similar, similarly disposed laterally spaced and aligned stops, and two laterally aligned dogs on each of the intermediate carriages, said dogs being disposed to cooperate with a respective set of stops.

6. Apparatus as claimed in claim 1, wherein each of the magnetic coupling means comprises at least one permanent magnet mounted on the end of one of two successive carriages, the end of the other of said two carriages having an armature cooperating with said magnet.

7. Apparatus as claimed in claim 6, wherein successive pairs of carriages in at least a part of the train of carriages have the same number of identical magnets, and comprising a shim of non-magnetic material disposed between the cooperating magnet and the armature of successive pairs of carriages in said part of the train, the shims associated with at least some of the pairs of carriages being of different graduated thicknesses, whereby to secure said graduation in magnetic coupling force between successive carriages in said part of the train of carriages.

8. Apparatus as claimed in claim 1, wherein the material guides on the intermediate carriages are disposed to lie below and adapted to support the upper run of material in the accumulator.

9. Apparatus as claimed in claim 8, comprising further material guides disposed below and adapted to support the lower run of material in the accumulator.
